DESIGN FOR A DISH

Samuel H. Berch, Beverly Hills, Calif., assignor, by mesne assignments, to Diced Cream of America Co., Los Angeles, Calif., a corporation of Delaware

Application July 19, 1947, Serial No. 140,385

Term of patent 14 years

(Cl. D44—15)

To all whom it may concern:

Be it known that I, Samuel H. Berch, a citizen of the United States, residing at Beverly Hills, county of Los Angeles, State of California, have invented a new, original, and ornamental Design for a Dish, of which the following is a specification, reference being had to the accompanying drawing, forming a part thereof.

I claim:

The ornamental design for a dish, as shown.

SAMUEL H. BERCH.
